(57) **CLAIM**

The ornamental design for an interchangeable lens for camera, as shown and described.

DESCRIPTION

FIG. 1 is a Front view of an interchangeable lens for camera showing my new design;

FIG. 2 is a Back view thereof;

FIG. 3 is a Top view thereof;

FIG. 4 is a Bottom view thereof;

FIG. 5 is a Left view thereof;

FIG. 6 is a Right view thereof; and,

FIG. 7 is a Perspective view thereof.

The dashed broken lines show portions of the interchangeable lens for camera that form no part of the claimed design. The dashed-dotted broken lines define a boundary of the design that forms no part of the claimed design.
